ELIZABETH MARY STIGALE, OF PHILADELPHIA, PENNSYLVANIA.

Design No. 3,729, dated October 26, 1869.

DESIGN FOR A FLOWER-SHADE AND PEDESTAL.

The Schedule referred to in these Letters Patent and making part of the same

---

I, ELIZABETH MARY STIGALE, of Philadelphia, county of Philadelphia, State of Pennsylvania, have originated a new Design for Flower-Shade and Stand, or Post, of which the following is a specification.

The accompanying drawing represents an outline elevation of a combined flower-shade and stand, made according to my design, A being a pillar or column, a the base, and b the cap of the column or stand, on which rests the base d of the glass shade B, enclosing flowers or ornaments, or other objects, the whole, excepting the said shade, being made of terra-cotta or other material.

I claim the design for flower-shade and stand, substantially as described, and represented in and by the accompanying drawing.

In testimony whereof, I have signed my name to this specification, in the presence of two subscribing witnesses.

ELIZABETH MARY STIGALE.
